CLAIM

I claim, the ornamental design for the reversible visor, as shown and described.

DESCRIPTION

FIG. 1 is a front elevational view of the reversible visor showing my new design;

FIG. 2 is a rear elevational view of the reversible visor thereof;

FIG. 3 is a left side elevational view of the reversible visor thereof;

FIG. 4 is a right side elevational view of the reversible visor thereof;

FIG. 5 is a top plan view of the reversible visor thereof;

FIG. 6 is a bottom plan view of the reversible visor thereof; and,

FIG. 7 is a perspective view of the reversible visor thereof.

The broken lines shown on the bill in FIGS. 1, 2, 5 and 7 are lines of stitching and form part of the claimed design. The word, "LOGO," shown in broken lines in the drawings is environmental matter and forms no part of the claimed design.
